UNITED STATES PATENT OFFICE.

OTTO BACHE AND CHARLES BERG, OF SAN FRANCISCO, CALIFORNIA.

SCRAPER FOR BOILER HAND-HOLES.

1,291,362.

Specification of Letters Patent. Patented Jan. 14, 1919.

Application filed April 2, 1918. Serial No. 226,834.

To all whom it may concern:

Be it known that we, OTTO BACHE and CHARLES BERG, a subject of the Emperor of Germany and a citizen of the United States, 5 respectively, residing at San Francisco, in the county of San Francisco and State of California, have invented new and useful Improvements in Scrapers for Boiler Hand-Holes, of which the following is a specification.

The present invention is an improvement upon that on which Letters Patent, No. 1,239,754, were granted to us on September 11, 1917.

15 Many stationary and marine boilers, such as the Edgemore boiler, have elliptical hand holes.

One object of the invention is to provide a 20 scraper particularly adapted for scraping such boilers.

In the accompanying drawing, Figure 1 is a side view of the invention shown as applied to a boiler. Fig. 2 is an end view of the same showing the inner surface of the 25 hand hole sheet. Fig. 3 is a sectional view on the line 3—3 of Fig. 2.

Referring to the drawing, 1 indicates the hand hole sheet of a water tube boiler and 2 the hand hole therethrough which in the present instance are approximately elliptical. 30 4 indicates a plate, also elliptical in form, and adapted to rest against the hand hole sheet 1 and having screwed to its inner surface as shown at 5 a wall 6 extending at a 35 uniform distance from the margin of the sheet and therefore also approximately of the form of an ellipse which, however, is incomplete, said wall 6 being adapted to fit against the inner edge of said hand hole and 40 forming a support for an elliptical cam 21. Said plate is formed integral with a central sleeve 7 terminating at its outer end in handles 8 extending in opposite directions on both sides of said sleeve. Said sleeve forms 45 a bearing for a spindle 9 having a handle 10 at one end, and to the other end of which is attached by a set screw 11, a tubular head 12, which carries a transversely extending guideway 13. In said guideway are guided 50 slide bars 14, the outer ends of which are enlarged in width, as shown at 16, to form blade carriers. Blades 17, each provided at opposite ends with cutting edges 18, are pivotally attached to said blade carriers by 55 screws 19, and thus automatically adjust their position to contact as closely as pos-

sible with the surface being scraped. In order that the blades may scrape the inner surface of the hand hole sheet close to the margin of the elliptical hand hole therein, 60 the blades must be caused to travel in elliptical paths as the spindle 9 is turned. For this purpose the elliptical cam 21 extends inwardly from the plate 4, and the blade carriers 16 are formed with transversely extending recesses 22 adapted to receive the inner edge of said cam. To reduce the friction between the blade carriers and the inner surface of said cam, said carriers are provided with rollers 23 which roll against said 70 inner surface.

The cutting edges of said blades are pressed against the inner surface of the hand hole sheet by a spring 24 coiled around the spindle 9 and compressed between the outer 75 end of the sleeve 7 and a collar 26 on said spindle. When said cutting edges are so pressed against said hand hole sheet, the spindle 9 is turned by means of a handle 10 secured thereto, thereby causing the cutting 80 edges of the blades to travel over said sheet and scrape the same.

In order to insert the blades through the hand hole in the boiler there is provided around the spindle 9 a short tube 28, from 85 which extend in opposite directions round bars 29. By turning said tube 28 on said spindle so that the bars 29 extend in the same plane as the handles 8, the bars 29 and handle 8 can be grasped by the two 90 hands and the plate can be drawn back from the blades a sufficient distance to allow, first one blade carrier, and then the other, to be inserted through the hand hole. One end of the elliptical cam 21 is cut away or 95 spaced from the plate, as shown at 30, to permit the device to be moved laterally, when the inner adjacent portion thereof has been inserted in the hand hole, a sufficient 100 distance to permit also the inner opposite portion, including the other end of said cam, to be so inserted. After the whole of the inner portion of the device has been inserted, the hands from the handles 8 and bars 29 are removed and the blades are then firmly 105 pressed against the inner surface of the hand hole sheet by the spring 24. Then, upon turning the spindle 9 by means of the handle 10 the blades can be moved over said surface while still pressing thereagainst, and 110 thereby, by reason of the elliptical form of the cam, and also by reason of the wall 6

fitting snugly in the hand hole, the inner surface of the hand hole sheet immediately around the hand hole can be thoroughly scraped.

5 The spindle 9 has a shoulder 31 engaging an end of a short tube 32 driven tightly into the sleeve 7 to limit the outward movement of the spindle.

We claim:—

10 In an implement of the class described, the combination of a rotary spindle, a bearing for the spindle provided with means for engaging the outer side of a sheet having a hole therethrough, blade carriers carried by

said spindle and removable transversely 15 thereto, resilient means for pressing the blade carriers toward the sheet, blades carried by said blade carriers, and a cam fixedly related to said means and adapted to extend inwardly through said hole when said means 20 engage said sheet and controlling the transverse movement of said blade carriers in their rotation with the spindle, a portion of the cam being spaced from said engaging means to facilitate the passage of the cam 25 through said hole.

OTTO BACHE.
CHARLES BERG.
